DESIGN FOR A PERFUME BOTTLE

Alfred Newman, New York, N. Y., assignor to Bombi Perfumer, Inc., New York, N. Y., a corporation of Delaware

Application August 5, 1947, Serial No. 140,712

Term of patent 14 years

(Cl. D58—8)

To all whom it may concern:

Be it known that I, Alfred Newman, a citizen of the United States of America, residing at New York city, in the county of New York and State of New York, have invented a new, original, and ornamental Design for a Perfume Bottle, of which the following is a specification, reference being had to the accompanying drawing, forming part thereof.

In the drawing

Fig. 1 is a top view of a perfume bottle showing my new design;

Fig. 2 is a front view;

Fig. 3 is a right hand view;

Fig. 4 is a back view; and
Fig. 5 is the other end view.

I claim:

The ornamental design for a perfume bottle,
as shown.

ALFRED NEWMAN.
